INVENTOR

William Gorman

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,732, dated November 2, 1869.

DESIGN FOR A DOOR-KNOB AND ITS ROSE.

The Schedule referred to in these Letters Patent and making part of the same.

To all whom it may concern:

Be it known that I, WILLIAM GORMAN, of New Britain, in the county of Hartford, and State of Connecticut, have invented a new and useful Design for a Door-Knob and its Rose; and I do hereby declare that the following specification, taken in connection with the drawings, making a part of the same, is a full, clear, and exact description thereof.

Figure 1 is a view, in perspective, of the knob and its rose.

Figure 2 is a view, showing the design of the top of the knob.

Figure 3 is a top view of the rose separately.

The design is intended to be used in the ornamentation of door-knobs and roses formed from a plastic material in moulds under pressure.

The central axis of the knob is projected in the form of a raised boss, *a*. This is surrounded by a star formed by a chain of arcs of circles, *b*.

From the point of junction of the arcs radiate, in alternation, clusters of leaves *c* and trefoils *d*, and the figure so made up is surrounded by a raised Gothic band, *e*.

The whole of this portion of the knob, above described, is flattened, and sunk below the adjoining portion, to give the article a lighter appearance.

The next member of the design is a bead-moulding, *f*, and the space between it and the edge moulding *g* is filled in with ornamental tracery in relief, as shown.

The rose, fig. 3, has a bead-moulding next to the shank, and the space between it and the edge-moulding *h* is filled with ornamental work of the same design as that upon the convex-face portion of the knob.

The under face of the knob, between the edge-moulding *g* and the shank, is composed of simple architectural mouldings, relieved by an intermediate embossed belt, *A*.

What I claim as my invention, and desire to secure by Letters Patent, is—

The ornamental design for a knob and its rose, substantially as described, and shown in the drawings.

WILLIAM GORMAN.
